UNITED STATES PATENT OFFICE.

LUCIAN HILL, OF NORTH BROOKFIELD, MASSACHUSETTS, ASSIGNOR TO
THEODORE C. BATES, OF SAME PLACE.

FASTENING-CLASP.

SPECIFICATION forming part of Letters Patent No. 293,247, dated February 12, 1884.

Application filed December 13, 1883. (No model.)

To all whom it may concern:

Be it known that I, LUCIAN HILL, of North Brookfield, county of Worcester, State of Massachusetts, have invented an Improvement in 5 Fastening-Clasps, of which the following description, in connection with the accompanying drawings, is a specification, like letters on the drawings representing like parts.

This invention relates to that class of fastening-clasps wherein a plate having an elongated eye contracted at one end is made to cooperate with a headed stud. In this class of clasps it has been common to employ spring-arms, the free ends of which extend across the slot in the plate, so as to yield laterally when acted upon by the headed stud and permit the stud to pass the arms, the latter springing in behind the stud and retaining the latter in the narrow end of the slot, the width of the slot at 15 that end being less than the diameter of the head of the stud.

With spring-arms as heretofore constructed it frequently happens, when inserting the head of the stud through the larger part of the slot 25 in the plate and moving the stud in the said slot, that the head of the stud passes between the arm and the plate, thus springing the arm upward away from the plate and destroying its efficiency. To prevent the possibility of 30 the entrance of the head of the stud improperly between the said arms and plate, I have provided the edges of the slot in the plate with a flange, a part of which latter is, however, omitted or cut away, to enable the acting ends 35 of the spring-arms to pass the edges of the slot and extend partly across the same, the arm or arms, one or more, constituting a lock-clasp.

My invention consists, essentially, in a lock-clasp composed of a plate provided with a slot 40 having a contracted extension and flanged, as described, and of an attached spring or springs constituting arms, one end of each arm being extended partially across the said slot, and being adapted to yield to permit the passage of 45 a headed stud into the narrowest end of the said slot, and then to spring behind and lock the stud therein.

Figure 1 represents one of my improved fastenings or lock-clasps separated. Fig. 2 represents the same closed; Fig. 3, a section of Fig. 1 on the dotted line $x^2 x^2$; Fig. 4, a similar

section on the dotted line $x^3 x^3$; and Figs. 5 and 6 are modifications to be described.

Herein my invention is shown as applied for use in connection with corset-steels; and referring to the drawings, A, B represent usual corset-steels, and C designates the usual headed stud, it being shown as attached to the steel B.

D represents the eye-plate, attached to the steel A by rivets e , the latter serving to hold not only the plate but also the spring-jaws f , there being in Figs. 1 to 5 two such jaws represented, and in Fig. 6 but one such jaw. These jaws rest close to and move upon the flat side 65 of the eye-plate D, and the said jaw or jaws, at their free ends, normally extend partially across the slot $h h'$, as represented in the drawings.

When providing the plate D with a slot, $h h'$, composed of a large eye and a more contracted extension, I provide the said plate more or less about the said eye with flanges 3 70 4, extending from the plate in the direction of its thickness, the depth of the said flanges 75 preferably equaling or being in excess of the thickness of the arm or arms used, so that the head of the headed stud, when being passed through the said slot or when being moved therein longitudinally, cannot pass laterally 80 beyond the edges of the slot and between the said jaws or arms f and the slotted plate D. The flange 3 prevents the possibility of any part of the spring-arm passing across the edges 85 of the enlarged round part h of the slot, the only part of the slot into and through which the enlarged head of the stud C can enter or pass. The part 4 of the flange about the small end of the slot $h h'$ serves as a rest or support 90 for the under side of the headed stud C, and holds the latter up level with the tops of the said arms, thereby preventing the head of the stud from falling below and during the backward movement of the stud from the small into 95 the larger part of the said slot, passing under the front ends of the said arms.

In Figs. 1 to 4 the spring-arms are produced from wire; but in Figs. 5 and 6 the said arms are composed of thin sheet metal, stamped or cut out to shape.

I do not claim the slotted plate or the spring-arms by themselves, as I know them to be old.

When but one spring-arm, *f*, is used, it may be composed of either flat sheet metal or of wire; and I also desire it to be understood that, if desired, the plate *D* may be applied or riveted upon the steel *A* so that the spring-arms will fall between the said steel and the plate *D*, the latter, when thus used, being countersunk or chambered to receive the spring-arms. In this latter modification the plate *D* will cover the spring arm or arms used, and the flanges *3* *4* will project toward rather than away from the person, as in the drawings.

I claim—

1. The herein-described plate, provided with a slot having a contracted extension, and having a flange, *3*, extended more or less about the large part of the said slot, combined with one or more spring jaws or arms, the front ends of which are adapted to extend partially

across the said slot, and to yield laterally to co-operate with the headed stud, substantially as and for the purpose set forth.

2. The plate *D*, slotted and provided with a flange, *4*, about the small end of the slot, combined with one or more spring jaws or arms extended partially across the slot in the said plate between the said flange *4* and the larger part *h* of the said slot, and with a headed stud adapted to rest at its under side upon the flange *4*, beyond the free end of the said arm, as and for the purpose described.

In testimony whereof I have signed my name to this specification in the presence of two subscribing witnesses.

LUCIAN HILL.
